UNITED STATES PATENT OFFICE

HARVEY HUBBELL, JR., OF BRIDGEPORT, CONNECTICUT

PORTABLE NIGHT LIGHT

Application filed October 27, 1927. Serial No. 229,037.

This invention relates to a portable night light, and has for an object to provide a light of this character which may be placed in any desirable position, such as on a table, under a table, a bed or other piece of furniture to give sufficient illumination so that objects on the floor or lower part of the room are visible and a person will not stumble over them, but without brightly illuminating the entire room.

It is also an object of the invention to provide an improved portable control means for the light.

It is a still further object of the invention to provide an improved construction of a light which is easily portable, is simple and attractive, and in which there is a guard and reflector for the lamp to protect the lamp against injury should some one step on it.

With the foregoing and other objects in view, I have devised the construction illustrated in the accompanying drawing forming a part of this specification. In this drawing,

Fig. 1 is a view showing the use of the light under a table or other piece of furniture.

Fig. 2 is a vertical section through the light proper showing the attachment plug cap and the portable control switch in elevation, the section being substantially on line 2—2 of Fig. 4.

Fig. 3 is a transverse section substantially on line 3—3 of Fig. 2, and

Fig. 4 is a bottom plan view of the light proper.

As illustrated this improved portable night light comprises a base 10 preferably of metal having a strengthening rib or flange 11 to rest on the floor or other support, and providing a chamber for lead wires and a greater portion of the mount for the lamp 12. This lamp mount comprises a block or body 13 of insulating material mounted in an opening in the top of the base and secured therein by any suitable means, such as screws 14.

The body has a recess 15 extending downwardly from its top wall in which are mounted the lamp contacts of any suitable type, usually a screw shell contact 16 to engage and receive the threaded outer contact 17 of the

lamp and the spring contact 18 to engage the central lamp contact. The screw shell contact rests on the bottom of the recess and is engaged by a laterally extending strap 19 carrying a binding post screw 20. The central spring contact 18 is secured by a rivet 21 on top of an insulating washer 22 resting on top of the strap 19. This rivet extends through the bottom wall of the recess and a strap 23 carrying a binding post screw 24. It will, therefore, be seen this rivet 21 secures both lamp contacts and their connecting straps and binding screws to the body, and it also forms an electrical connection from the strap 23 to the spring contact 18. The binding screws and straps 19 and 23 are preferably mounted in recesses 41 on the lower side of the body member 13 so that they are protected but at the same time are easily accessible. In the opposite side walls of the base are mounted insulating bushings 25 for passage of the lead wire cords 26 and 27. Carried by the base over the lamp is a protecting hood and reflector 28. This hood is made of metal of sufficient thickness to sustain considerable weight and is supported by the base through upwardly extending screw bars 29 passing through and threaded into ears 30 on the inside of the hood, and these screws are surrounded by tubular elements 31 to strengthen the screws and help sustain the hood and to give a neat and attractive appearance. The inner wall 32 of the hood and reflector may be painted or enameled white to reflect the light from the lamp laterally and give a greater illumination of the floor and other objects thereon, but it will be understood this hood prevents the general illumination of the room as practically all the light from the lamp will be reflected downwardly and laterally. The hood being of considerable strength forms a complete protection for the lamp and it is mounted so that it will sustain considerable weight and will prevent injury to the lamp should some one step on it or objects be dropped on it.

The flexible cord 26 is connected to any standard type of attachment plug cap 33 having the usual contact blades 34 for insertion in the wall or floor receptacle. The flex-

ible cord 27 leads to any suitable type of portable switch 35, the present type shown being one of the so-called push through switch type having a transversely slid able member 5 operated by the buttons 36 in the usual manner. Each of these cords, as is usual, carries two lead wires, one of these wires, the wire 37 being a continuous or through wire from one of the contact blades to the switch and 10 for purposes of appearance and assembly it passes into the base and around the central body 13, as shown in Fig. 4. The other wire is cut and the lamp is mounted in this cut wire, the section 38 leading to the other contact blade of the cap and is connected to one of the lamp contacts, while the other section 39 leading from the switch is connected to the other lamp contact. In the present case the section 38 is connected through the binding screw 24 to the central lamp contact while the section 39 is connected through the binding screw 20 to the screw shell lamp contact. It will, therefore, be apparent that the portable switch controls the lamp.

25 It will be obvious from the foregoing description that the lamp is easily portable and may be located on a table in a bed room or nursery or in a hospital, or it may be located under the table, under a bed or any other 30 piece of furniture, or in any location desired, and the cap plugged into any available outlet receptacle. The control switch 35 is also easily portable and may be placed where it is easily accessible. For instance it may be placed on top of a table 40, as shown in Fig. 1, where it is easily accessible, and if the table is by the side of a bed it may be easily reached from the bed, or the switch may be placed under the pillow. If a person wishes to get 35 up during the night and he does not wish to illuminate the room with the regular lights this lamp will give sufficient illumination so that all parts of the floor and objects thereon can be sufficiently seen to prevent stumbling over them. The light proper is so constructed as not to be liable to be easily damaged so that it may be used on the floor and similar locations.

Having thus set forth the nature of my invention, what I claim is:

50 1. A portable night light comprising an easily portable base to rest on a support, an insulating body member mounted in the base, lamp contacts and a lamp carried by said member, a substantially opaque reflector hood and lamp protector mounted over the lamp and spaced above the base to reflect the light downwardly and laterally, and upright supports between the hood and the base to mount 55 the hood on the base.

60 2. A portable night light comprising a portable base having an opening through its top wall, an insulating body mounted in said opening and provided with a recess extending downwardly from the top thereof, lamp

70 socket and central contacts mounted in said recess, upright supports extending upwardly from the base, and a substantially opaque dome shaped reflector carried by said supports over the recess and spaced above the same to reflect the light downwardly and laterally.

75 3. In a portable night light, a portable base, a lamp carried by the base, a substantially opaque protective hood and reflector mounted over the lamp and spaced above the same to deflect the light downwardly and laterally, spaced rigid supports for the hood extending upwardly from the base and secured to the base and hood, an attachment plug cap, a control switch spaced from and portable independently of the base, a through wire leading from the cap to the switch through the base, lamp contacts carried by the base, a lead wire from the cap connected to one of the lamp contacts, and a lead wire from the switch connected to the other lamp contact so that the lamp is controlled by said switch and the switch is portable independently of the cap and its lead wires.

80 4. In a portable night light, a portable hollow base having an opening in its top wall, an insulating body member mounted in said opening and having a recess extending downwardly from its upper wall, lamp contacts and a lamp mounted in said recess, a protective hood and reflector mounted on the base over the lamp and spaced from the base, binding screws mounted on the lower part of the body member having electrical connections 85 with the respective lamp contacts, an attachment plug cap for connection to an outlet, a portable control switch, a through lead wire from the cap to the switch, a second wire from the cap connected to one of the binding screws, and a second wire from the switch to the other binding screw so that the lamp is controlled by said switch.

85 5. In a portable night light, a portable hollow base adapted to rest on a support, a lamp 90 socket carried by the base including lamp contacts, a protective hood and reflector mounted over the socket and spaced therefrom to reflect the light laterally and downwardly, upwardly extending supporting bars secured to the base and hood and supporting the hood above the base, lead connections for connecting the socket to an outlet, and a switch for controlling the socket.

95 In testimony whereof I affix my signature, 100
HARVEY HUBBELL, JR.
